Int. Cl. D8—05

U.S. Cl. D8—88

FIG. 1 is a view in side elevation of a telescopic levering tool for winches and chain binders, showing my new design, the same being shown in extended position of adjustment.

FIG. 2 is a view in side elevation, similar to FIG. 1, at an enlarged scale showing the tool in retracted position.

FIG. 3 is an elevational view, as viewed from the left in FIG. 2 in the direction of the arrows 3—3.

FIG. 4 is a top plan view as viewed from the top in FIG. 3 in the direction of the arrows 4—4.

FIG. 5 is a bottom plan view as viewed from the bottom in FIG. 3 in the direction of the arrows 5—5.

I claim:

The ornamental design for a telescopic levering tool for winches and chain binders, as shown.
